HOUSING

John H. Shrock, La Porte, Ind., assignor to
Mechanovent Corporation of Indiana, La Porte,
Ind., a corporation of Indiana

Application December 31, 1938, Serial No. 248,849

1 Claim. (Cl. 98—39)

This invention relates to a heating and air conditioning unit. It has for one object to provide in combination in such a unit a chassis which includes the essential parts of the mechanism, such as blowers, humidifiers, heaters, filters and the like and includes the necessary structural members for their support so as to provide a unit chassis complete with the operation of a hood.

Another object is to provide a separate hood which may be removably mounted or secured to the chassis and to provide separable connection or latching means positioned partially upon the hood and partially upon the chassis.

Another object is to provide a method of assembly and installation of such a heating or air conditioning device.

Other objects will appear from time to time in the specification and claim.

The invention is illustrated more or less diagrammatically in the accompanying drawings, wherein:

Figure 1 is a side elevation of the chassis before final installation into a building, partially shown in section.

Figure 2 is a partial vertical section through the building showing the total assembly in plan.

Figure 3 is an inside front elevation of the apparatus with parts broken away and parts in section.

Figure 4 is a sectional view through the wall structure with the apparatus in place but without the hood.

Figure 5 is a transverse view illustrating wall and building portions in section and showing the chassis positioned away from the wall and the hood positioned away from the chassis.

Like parts are designated by like characters throughout.

1 indicates a wall of a building. A device may be installed in a partition and is not limited to the specific installation in a wall. As shown the wall is provided with an opening 2. A baffle or shutter mechanism 3 may be provided in the opening 2. As shown a floor beam 4, may be provided to support a floor structure 5. A window opening 6 is shown above the opening 2 and a window structure or assembly 7 is provided in it. Adjacent the opening 2 is a depression or hollow 8 formed in the wall or partition 1 and arranged to receive a portion of the unit.

The chassis of the unit is provided with a section or portion 9 which as shown, for example, in Figures 1 and 2 is both lower and narrower than the remaining portion of the chassis. This portion 9 is of such size as to fit into the space 8 when the chassis is in final position in the wall.

While the details of the chassis and the assembly of the parts upon the chassis, might be widely varied they comprise in addition to the reduced section 9 above mentioned, a larger por-

tion which is both wider and higher than the section 9. This includes a pair of structural frame members 10, laterally extending back plate members 11, diagonal stiffening braces or plates 12, floor or bottom plates 13 and may include other structural members. In general, it is sufficient for the purposes of this invention to provide such structural members as are necessary to form a self sustaining chassis frame. To these frame members are added, if desired, supports 14 and 15, which removably support various portions of the assembly. Preferably, the supports may be arranged to slidably receive the parts which they carry so that these parts are moved into place and may be removed just as drawers are pushed into or removed from their supports. The supports 14, for example, may carry a heating coil and the supports 15 may carry a frame member 16 of a blower assembly which includes one or more fans or blowers 17. As here shown, a set of supports 18 is provided and these supports may carry a filter 19.

Positioned below the supports 18, or made as a part of them if desired, are two plates 20 and 21 in which are provided respectively openings 22 and 23. Dampers or doors 24 and 25 are arranged to close the openings 22 and 23 respectively. The dampers are opened by one or more levers 26 pivoted upon a support 27. A pivoted connecting rod 28 joins one arm of the lever 26 to the damper or door 24 and a pivot connecting rod 29 joins the other arm of the lever 26 to the door or damper 25. As shown, particularly in Figure 5, the arrangement of the parts just described is such that when the one door is closed the other may be open, or an intermediate position of adjustment may be used in which both doors are partially open.

Although the particular invention herewith shown and described is not limited to the structural details shown, it is ordinarily preferred to provide suitable openings in the frame and supporting members to permit the necessary electrical and liquid connections. Thus, the plate members 11 may be perforated, as at 30, to permit making of electrical connections with wall plugs or sockets. The members 13 may be provided with openings as at 31 to permit the making of liquid connections with sources of steam, water or drainage connections. The plates 10 may also be perforated, as at 32, to permit the passage of pipes 33. It will be noticed, in particular in Figures 1 and 5, that these passages are preferably elliptical or at least enlarged beyond the size of the pipes which pass through them. Since the heating coil which is positioned in register with the passage 32 is preferably inclined toward one end, the connections at the two ends of the heating coil are ordinarily not on exactly the same level. By the provision of

an elliptical or enlarged passages it is possible to position the coil with its high end either to the right or to the left and this simplifies the problem of assembly and installation.

As a means of closing or enclosing the chassis and the parts which it covers, there is provided a hood 34. This hood is provided with end portions 35 and a top 36 which is cut away as at 37 and a grille 38 supported on members 39. While the hood may be of almost any shape it is preferably provided with rounded corners 40 as shown particularly in Figure 3. It may also be provided with an ornamental band 41.

As a means for removably securing the hood to the chassis a latch construction is provided. This includes a latch bar 42, provided with an offset portion 43 intermediate its ends. Bearings 44 are provided for the latch bar and are positioned preferably on the front wall of the hood. The latch bar is provided preferably, as at either end, with offset latch portions 45, which may be moved into engagement with latch abutments 46 positioned in the form here shown on the chassis and in the particular form herein shown positioned on the support members 10 of the chassis. As a means for operating the latch bar and moving it into and out of engagement with the latch abutment members 46 there is provided a pivoted member 47 which as shown is pivoted on the hood and preferably on its front wall, and has an irregular shaped aperture 48. An operating shaft 49, may be removably inserted in the aperture 48 in the member 47 and is provided at its outer end with an operating handle 50. A link 51 is pivoted at one end upon the member 47 and at its other end engages the offset portion 43 of the latch rod 42. The handle 50 might be fixed to the member 47 if desired, instead of being removable, as shown.

The hood may also be provided on its front wall with an opening 52 corresponding in shape, in size and position to the opening 23 in the member 21. A fixed grille 53 may be positioned in the opening 52 and may, if desired, be formed of inclined strips or slat members, as shown. On the inner face of the hood, with respect to the slats 53, are pivoted and downwardly hung flap members 54. These tend to close in case of a sudden draft from inside of the device.

The use and operation of the invention are as follows:

In general, the device may be considered as comprising an air treating apparatus. When it is to be installed it will ordinarily be installed at least partially within a wall or partition and a cavity or opening will be provided, into which a part of the apparatus fits. Assembly of parts of the mechanism on the chassis and the making of connections may be carried out as and when desired and convenient.

The device may be put, first, not in but adjacent the opening in the wall. In the position shown in Figure 5 the chassis will be close to the wall. The parts which are to be mounted on the chassis may then or later be put in place, if they have not already been put in place. Preliminary connections may be made, and all of this done while the chassis is stripped or without the hood. Frequently it is advantageous to keep the hood entirely away during the process of assembly or installation to prevent damage to the hood.

When assembly of the device is completed and it is seated in the opening provided for it and all of the connections have been made so that no further work remains to be done the hood is then put in position covering and surrounding that part of the assembly which does not lie within the cavity in the wall and the hood is latched in position and afterward if it is desired to remove the hood for any reason, it is merely unlatched and the apparatus is then available for inspection or repair.

By the methods of assembly and installation above outlined, the device may be treated as a chassis and during the period of installation, 15 when the hood is most likely to be damaged, the hood may be kept away and it is only after the work of installing the device is completed that the hood is installed. By assembling the operative parts on a chassis without ornamental 20 parts the operation of assembling is simplified and safeguarded.

The modification of installation may thus be summarized as follows:

First the chassis with or without the parts 25 which it is to carry will be placed close to, or within, the cavity into which it is finally to be positioned. Thereafter whatever parts of the mechanism have not been installed will be added. The necessary electrical and fluid connections 30 will then be made. These may be made before or after the chassis has been moved into its final position. When the chassis has been put into final position; all parts have been mounted upon it and all connections have been made, the 35 hood is removably positioned so as to cover all of the exposed parts of the chassis and the working mechanism which it carries.

I claim:

40 In combination, an air treating apparatus suitable for insertion in a recess in a fixed room wall, which recess is in communication with the exterior of the building of which the wall member forms a part, a chassis including a portion formed to penetrate the recess and a portion 45 formed to abut against the inner face of the wall exterior to said recess passage, means on the chassis adapted for communication with a passage through the wall, a fluid connection between said chassis and said wall, said chassis being open on the portions away from said fixed room wall, supports on said chassis adapted to receive operating elements positioned upon said chassis and inserted through said open portion thereof, and a removable housing for said chassis, 50 said housing extending about and above said chassis and enclosing the exposed portions thereof, and forming with said fixed room wall a complete closure for said chassis, said chassis and said housing being both independently supported upon the floor of the room in which they are located, the fluid connection of the chassis constituting the sole connection between the chassis and the wall, said housing including air inlet and outlet passage elements aligned with appropriate portions of the chassis, means in said passage elements for controlling the passage of air therethrough, and externally operable 55 readily disconnectible means for securing said housing in relation to said chassis.

J. H. SHROCK.
